CLAIM

The ornamental design for an arcuate eyeglass lens with a vertical semi-hexagonal aperture, as shown and described.

DESCRIPTION

FIG. 1 is a front environmental view of a pair of arcuate eyeglass lenses with a vertical semi-hexagonal aperture, showing my new design;

FIG. 2 is a front perspective view of an arcuate eyeglass lens with a vertical semi-hexagonal aperture;

FIG. 3 is a front view thereof;

FIG. 4 is a rear view thereof;

FIG. 5 is a left side view thereof with a right side being a mirror image;

FIG. 6 is a top view thereof; and,

FIG. 7 is a bottom view thereof.

The broken line showing of a second arcuate eyeglass lens with a vertical semi-hexagonal aperture and an eyeglasses frame shown in FIG. 1 is for the purpose of illustrating environment and forms no part of the claimed design.
